Des. 176,258
Patented Dec. 6, 1955

176,258

COVER FOR THE MIXING VESSEL OF A FOOD AND DRINK MIXER AND BLENDER

Joseph A. Hill, Glen Ellyn, Ill., and James M. Katzfey,
Saukville, Wis., assignors to John Oster Manufacturing
Company, Milwaukee, Wis., a corporation of Wisconsin

Application September 3, 1954, Serial No. 32,153

Term of patent 14 years

(Cl. D89—1)

Fig. 1.

Fig. 2.

Fig. 3.

Figure 1 is a perspective view of a cover for the mixing vessel of a food and drink mixer and blender, embodying our new design;

Figure 2 is a side view of the cover; and

Figure 3 is a top view thereof.

We claim:

The ornamental design for a cover for the mixing vessel of a food and drink mixer and blender, as shown.
